UNITED STATES PATENT OFFICE.

LEONARD F. HEITZ, OF LAKE MILLS, WISCONSIN, ASSIGNOR TO THE CREAMERY PACKAGE MFG. COMPANY, OF CHICAGO, ILLINOIS, A CORPORATION OF ILLINOIS.

GUDGEON STRUCTURE FOR CHURNS AND BUTTER WORKERS.

Application filed March 16, 1922. Serial No. 544,310.

The invention relates to combined churn and butter-workers of the type comprising a churn drum rotatably supported at its ends and carrying revoluble working rolls, and 5 relates more particularly to the operating and supporting means for the drum and the rolls.

Churn drums are commonly constructed of wood, to the wooden heads of which are 10 secured gudgeons for their operative support. The working rolls also are commonly journaled in the wooden heads. The distortion of the drum, due to the action of its liquid contents, affects the alinement of the 15 gudgeons and also of the roll bearings, and causes much wear, noise and loss of power.

The object of this invention is to provide an improved gudgeon supporting construction including a final gear and rigidly positioned end bearings for the working roll journals.

Other objects and advantages will be apparent in the following detailed description of a preferred embodiment of my invention 25 which I have illustrated in the accompanying drawings.

In the drawings Fig. 1 is a plan view of a preferred construction of churn and butter-worker in which only the end portions 30 of the churn drum are shown.

Fig. 2 is a front elevation illustrating the driving mechanism and supporting standards.

Fig. 3 is a longitudinal vertical section 35 taken on the plane of the medial line of Fig. 2.

Fig. 4 is a vertical cross section taken on the plane of the line 4—4 in Fig. 3.

Fig. 5 is a horizontal section taken on 40 the plane of the line 5—5 in Fig. 4.

In the present embodiment, the frame of the machine comprises a front standard 1 and a rear standard 2, rigidly connected at the top as by a spacer tube 3 and rod 4, the 45 latter carrying end cap nuts 5 which clamp the standards. The lower portions of the standards are preferably rigidly spaced by a pair of side stringer tubes 6 suitably clamped in the legs of the standards as at 50 7. Forward extensions of the stringers 6 carry an outer bearing support 8 and an inner bearing support 9 which accommodate the driving mechanism.

The drum or body of the churn consists 55 of a cylinder 10 having heads 11 and 12, and

binding hoops 13 to secure the usual stave construction. A door 14 gives access to the interior of the churn. To the front head 11 of the drum is fixed a sectional gudgeon structure comprising a flanged base section 15 rigidly secured to the head as by bolts 16, and an outer spider section 17 providing a journal 18 alined with the axis of the drum and having radial arms 19 supporting a ring gear 20. The spider, journal and gear comprising the outer section 17 preferably are of integral construction rigidly secured to concentric projecting portions 21 of the base 15 as by bolts 22. This sectional construction facilitates the manufacture and 70 assembly of the gudgeon structure.

As illustrated herein, the journal 18 is operatively supported in a bearing sleeve 23 mounted in an appropriate bearing box 24 formed in the standard 1 and constructed for automatic lubrication by an oiling ring 25.

The ring gear 20, and thereby the churn drum, is driven by a pinion 26 rigidly mounted on a shaft 27 rotatably supported 80 at its ends in bearings 28 and 29 in the standard 1 and outer bearing support 8 respectively. A drive pulley 30 is mounted on the outer portion of the shaft 27 and is provided with a hub bearing 31 freely rotatable 85 on the shaft.

The inner periphery of the pulley drum is arranged for operative association with a suitable clutch device carried by the shaft 27 and herein illustrated as comprising one 90 or more shoes 32 pivoted at one end on arms 33 extending from a hub 34. A shift collar 35 splined on the hub 34 serves to operate sets of toggle members of well known construction which selectively force the shoes 95 32 into frictional contact with the pulley. The collar 35 may be annularly grooved to receive a pair of pins 36 carried by a shifting lever 37 pivoted at 38 on a bracket mounted on the inner bearing support 9.

The hub 34 is fixed on the outer end of a sleeve 39 freely rotatable on the shaft 27 and extending inwardly from the pulley hub through the inner bearing support 9, the latter being provided with a suitable bearing 100 for the center portion of the sleeve.

The inner end of the free running sleeve 39 terminates in a clutch drum 40 about which is operatively associated a contractible friction member 41 carried by a housing 110

42, the latter having a hub 43 keyed in fixed relation to the shaft 27. The friction member 41 may be operated to grip the drum 40 by means of the pivoted cam finger 44 controlled by the beveled end of the sliding collar 45. The latter may be operated to engage or disengage the clutch member by the lever 46 pivoted on a bracket 47 mounted on the standard 1, and having a yoke carrying a pair of pins 48 in engagement with an annular groove in the collar 45. It will now be apparent that with the operative engagement of the two clutches described a direct drive is established from the pulley 30 through the shaft 27 to the pinion 26, and gives the higher speed desirable in the churning operation.

As illustrated herein the pulley 30 is provided for an initial drive by belt, but it will be obvious that a sprocket or gear may be substituted for the pulley to accommodate a chain or gear motor drive, having associated therewith if desired a friction drum for co-operation with the clutch shoes 32.

For the butter working operation lower speed is attained by means of back gearing and another clutch. A shaft 49, having suitable end bearings supported in the standard 1 and in the inner bearing support 9, carries a fixed gear 50 permanently in mesh with a pinion 51 preferably integrally formed on the sleeve 39. The shaft 49 also carries a fixed pinion 52 permanently in mesh with a gear 53 mounted for free rotation on the shaft 27. The hub of the gear 53 is axially extended to form a clutch drum 54 with which is operatively associated a clutch construction similar to that last described and controlled by the finger 55 and sliding collar 45, the clutch housing hub 56 being keyed in fixed relation to the shaft 27.

The shift collar 45 is arranged in relation to the two clutch operating fingers 44 and 55 so that in intermediate position both clutches are disengaged with the drum members running free on the shaft 27, and in either end position one of the clutches is engaged while the other is free. When running at the higher churn speed with the front clutch engaged, power is transmitted directly to the shaft 27 while the back gears carried by the shaft 49 idly rotate the gear 53. When it is desired to operate at butter-working speed, the collar 45 is shifted to engage the rear clutch and release the front clutch, whereupon the gear reduction of the back gears is availed by transmission through the pinion 51, gear 50, shaft 49, pinion 52, gear 53 and the now engaged clutch hub 55 to the shaft 27 and drive pinion 26.

For the operation of the butter-working rolls I have provided a shaft 57 supported at its front end in a suitable bearing 58 mounted in the upper portion of the inner

bearing support 9. The shaft 57 is rearwardly supported in a bearing formed in the gudgeon journal 18 and extends axially therethrough to an end bearing 59 suitably secured to the head 11 of the churn.

The forward portion of the shaft 57 carries a sliding gear 60 freely rotatable on the shaft and permanently meshed in driven relation to the back gear 50. The forward end of the hub of the gear 60 is diametrically recessed to form a pair of laterally opening pockets adapted to receive the cross pin 61 fixed in the shaft 57 and by which the shaft is driven when engaged. The gear 60 may be shifted without disengagement from the gear 50 to selectively engage or disengage the pin 61 by means of a shifting yoke 62 engaging an annular groove in the gear hub, the yoke being longitudinally slideable on a bridge member 63 connecting the inner bearing support 9 with the standard 1. The yoke 62 may be operatively controlled by a hand lever 64 pivoted on a lateral extension of the member 63.

Rearwardly of the gudgeon bearing, the shaft 57 carries a fixed gear 65 by which the working rolls are driven. The working rolls 66 (Fig. 5), of which four are illustrated herein, are journaled at the rear of the churn in suitable bearings carried by the plates 68 fixed in the rear drum head, and are supported at their front ends by shafts 67 extending through suitable packing glands mounted in the front drum head. The latter comprise a gland 69 countersunk in the head and secured thereto as by bolts 70. A gland nut 71 is removable outwardly along the shaft 67.

The forward ends of the shaft 67 are journaled in bearings 72 provided in a pair of the arms 19 forming part of the gudgeon and ring gear supporting structure. Rearwardly of the bearings 72 and laterally aligned with the gear 65, a gear 73 is fixed on each of the roll shafts 67, the inner pair of gears 73 meshing with the gear 65, and the outer pair meshing respectively with the inner pair of gears. The base section 15 of the gudgeon structure is constructed with laterally open walls to accommodate the gears 73.

By disengaging the gear 60 from the pin 61, the former will run free on the shaft 57 in the churning operation, and the rolls 66 will remain in stationary relation to the churn drum. Upon engagement of the gear 60 with the cross pin in the shaft 57, the several rolls are operatively rotated by their gears 73 in driven mesh with the central gear 65.

It will now be apparent that the construction herein provided assures a fixed alignment and spacing of the end bearings of the roll shafts, thus maintaining the roll driving gears in smooth running relation unaf-

fected by the distortions which may occur in the drum and head. Another advantage to be noted is the space provided between the gland nuts and the gears, which enables the 5 removal of the nuts along an unobstructed portion of substantial length of the shafts 67 for repacking the glands without disassembling the gears or other of the driving members.

10 Other features of my invention, relating to the driving mechanism herein described and illustrated, are set forth and claimed in my copending application Serial No. 212,367, filed August 12th, 1927, which lat- 15 ter has been divided from this application.

I claim as my invention:

1. In apparatus of the class described, a gudgeon structure adapted to support a rotatable drum having rotatable roll shafts 20 extending outwardly therefrom, comprising, in combination, a base section adapted to be rigidly attached to said drum, and a unitary outer section secured thereto including a main supporting journal and a gear for the 25 operative rotation of said drum, said outer section having bearings formed therein for the outward support of said roll shafts.

2. In apparatus of the class described, a

gudgeon structure adapted to support a rotatable drum having packing glands in a 30 wall thereof and having rotatable roll shafts extending outwardly through said glands, comprising, in combination, a base portion adapted to be rigidly attached to said drum, an outer portion forming a journal, and lateral extensions formed on said outer portion having bearings therein for the outward support of said roll shafts, said bearings being substantially spaced from said drum wall to expose portions of said shafts between said wall and said bearings for the 35 opening of said glands longitudinally of said shafts.

3. In apparatus of the class described, a gudgeon structure adapted to support a rotatable drum having rotatable roll shafts 40 extending outwardly therefrom, comprising, in combination, a base portion adapted to be attached to said drum, a journal portion aligned with the axis of said drum, and lateral extending portions having bearings 45 therein for the outward support of said roll shafts.

In testimony whereof I have hereunto set my hand.

LEONARD F. HEITZ.
